SHINGLE AND FASTENING THEREFOR

Addison Applegate, Liberty, N. Y.

Application August 4, 1931. Serial No. 554,977

13 Claims. (Cl. 108—33)

This invention relates to shingles and, with particularly, to an improved design of shingle and fastening means therefor.

One of the principal objects of this invention is to provide an improved design of so-called flexible or felt base shingle, together with a novel form of fastening or locking device for adjacent shingles.

Another object relates to a shingle structure which is designed to allow for contractions and expansions of the roof or other surface to be shingled.

A further object relates to a shingle of the folded-back edge or corner type, which is provided with means for preventing water "backing up" between overlapped shingles and eventually reaching the roof proper.

A feature of the invention relates to a novel form of locking device for flexible or felt base shingles which device also is useful in aligning successive shingle courses.

A further feature resides in a method of locking the points of adjacent shingles to a lower or underlapped shingle.

A further feature resides in a shingle arrangement whereby all metal fastening such as nails, shingle locks, etc., are completely covered.

A further feature relates to a novel form of locking device for shingles which serves to retain at least three shingles in position.

A still further feature resides in a shingle lock which materially facilitates the laying and aligning of shingles.

A further feature relates to an improved form of "starter" shingle.

A still further feature relates to a shingle having a turned back edge or corner, the edge or corner being perforated, slotted, etc., to allow water to flow freely therethrough.

Other features and advantages not specifically enumerated will be apparent after a consideration of the following detailed description and the appended claims.

While the invention will be described hereinafter as applied to one known type of shingle such as a felt base or flexible shingle, it will be understood that the broad aspects of the invention are equally well applicable to any other type of shingle.

In the drawing—

Figure 1 shows a portion of a roof or other surface shingled in accordance with the invention;

Fig. 2 is a detailed sectional view of the shingling of Fig. 1;

Fig. 3 is a detailed view of an individual shingle. This view shows the novel folded corner and locking device according to the invention;

Fig. 4 is a detailed view of a starter shingle according to the invention;

Fig. 5 illustrates the manner in which the starters and regular shingles are locked together;

Fig. 6 is a partial sectional view taken on the line 6—6 of Fig. 1;

Fig. 7 is a plan view of the preferred form of shingle lock according to the invention;

Fig. 8 is an end view of the lock of Fig. 7;

Fig. 9 is a plan view of a modified form of shingle lock; and

Fig. 10 is an end view of the lock of Fig. 9.

Referring more particularly to Figs. 1 to 5 the numeral 1 represents a surface to be shingled such as a roof or the like. It is preferred, in accordance with the present invention, to employ shingles of the square or diamond shaped type although this form is not necessary and other desired shapes of shingles may be em-

ployed so long as the shingles have abutting edges that are to be locked together. Thus there is shown in Fig. 3 a shingle 2 which may be of the well known flexible or felt base type. The manner of manufacturing the material for such a shingle is well known in the art and forms no feature of the present invention. How-

ever, it will be noted that the shingle 2 is pro-

vided with a turned back corner 3 and that the edge of the turned back corner is perforated or slotted as indicated by the numeral 4 for pur-

poses described hereinbelow. It will also be noted that the turned back corner of shingle 2 is not a simple V-shape but has the edge cutout as indicated by the numeral 5 so as to allow

the shingle to adapt itself, when in locked as-

sembled position, to the normal expansions and contractions of the roof 1. The shingle 2 is ad-

apted to be applied to the roof so that the turned back edge or corner forms the lower edge of the shingle in which case the said lower edge may be fastened in position by means of a brad, nail or other suitable member 6 which passes through the turned back corner 3 and thence into the material of the roof 1 as shown

clearly in Fig. 2. Attached to each of the shingles 2 is a shingle locking device 7 which may be in the form of a metal strip, wire or other similar material as shown in plan view in Fig. 7, and in end view in Fig. 8. As shown in Figs. 1

to 5 the preferred form of this lock is that of a T-shape comprising a horizontal portion 8 and a vertical portion 9. As shown more clearly in Fig. 6 the locking member 7 is attached to the shingle by means of the struck-up lugs 10 and 11 which pass through the body of the shingle 2 and are clinched on the opposite face thereof thus rigidly fastening the lock member 7 in position with the portion 9 in alignment with opposite corners of the shingle. As shown clearly in Fig. 6 the portion 9 is adapted to be bent back upon itself and engage the abutting corners 12 of adjacent shingles 2 as clearly shown in Figs. 1, 4 and 6, it being understood that the shingles 2 are preferably laid in diagonal fashion as shown in Fig. 1 so that the turned back edges of the shingles are substantially parallel to the lower edge of the roof. Preferably the brads 6 are omitted and the turned back portion 9 on another shingle may be relied upon to hold the corner 5 in place.

In accordance with the usual practice the roof is shingled from the lower edge upwards and for this purpose starter shingles 13 may be employed. While any well known form of starter shingle may be used it is preferred to employ a starter shingle of the type shown in Fig. 4 of the drawing which is substantially trapezoidal in shape, the lower straight edge of which is adapted to be folded back upon itself along the line 14 (Fig. 4). As will be noted from Fig. 4 the sides of the starter shingle are cut back or slitted as indicated by the numeral 15, these slits being located on the line 14 at which the shingle edge is bent back. For the sake of clearness, of course, Fig. 4 is shown with the starter shingle in its original shape before the lower edge has been turned back upon itself.

Fig. 5 shows a starter shingle 13 as it is actually applied to the roof. The shingle is fastened to the roof by means of nails, brads or other similar devices 16 which pass through the free turned back corners of the starter shingle. As shown more clearly in Fig. 1 the starter shingles are fastened in position on the roof with the turned back edges 17 preferably in abutting relation so that the edges 18 are in alignment and, therefore, parallel to the roof edge. Each of the starter shingles is provided with a locking device 7 similar to the locking devices provided on the regular shingles 2 as described hereinabove. When the complete course of starter shingles has been laid and fastened in a manner described above the first course of regular shingles may be laid. The manner of laying the regular shingles is schematically shown in Fig. 4 wherein it will be seen that the turned back corner 3 of a regular shingle is adapted to pass through the slits 15 in adjacent starter shingles. Thus the lower edge of each regular shingle is locked in position by the turned back edge of the adjacent starter shingles as shown in detail in Fig. 2 of the drawing. The regular shingles 2 are laid preferably with their corners 12 abutting each other and in order to facilitate the accurate laying of the regular shingles the locking strips 7 on the starter shingles may be used for lining up the regular shingles. Thus the locking members 7 on the starter shingle may be provided with a small depression or other distinguishing mark 19 to indicate the proper point at which the corners of adjacent shingles are to meet. When two adjacent shingles have thus been laid the portion 9 of the adjacent

locking strip is turned back upon itself as shown in Figs. 1, 2, 4 and 6 so as to clamp the corners of the shingles against the starter shingles. If desired the turned back portion 9 may be rigidly fastened by means of a brad or nail although this is not absolutely necessary since the locking members 7 may be made out of relatively heavy metal so that when bent back they may be hammered down and their natural rigidity will effectively clamp the shingle corners in position.

However, in accordance with the present invention it is preferred to simply bend the portion 9 of each locking member back upon itself so as to provide a slight clearance between the end of the portion 9 and the starter shingle. The reason for allowing this clearance is so that the turned back corners 3 of the shingles in the next course may be locked underneath the portion 9 of the locking members. Thus, as shown in Fig. 1 the next course of shingles is laid with the turned back corners 3 lying in the angle between the converging edges of adjacent shingles. However, due to the special shape of the turned back edges 3 the shingles are locked against vertical displacement but, nevertheless, are not subjected to buckling when the roof 1 expands and contracts as would be the case if the corners 3 were completely triangular and fitted closely between the converging edges of the two shingles underneath. It has been found that the cutting away of the corners 3 as indicated by the numeral 5 provides a sufficient interlock between the shingles without, at the same time, preventing the shingle buckling when the roof expands or contracts.

As described hereinabove the turned back edge of each of the regular shingles is perforated or slitted as indicated by the numeral 4 so as to allow free egress to any water that may accumulate beneath the shingle thus preventing the water under a shingle backing up and eventually reaching the roof proper as has been found to be the case where the lower edges of the shingles are unperforated. When a course of regular shingles has been laid as described hereinabove the locking members 7 as well as the brads or nails 16 are completely covered and are thus protected from the weather.

It will also be noted that the locking members 7 in successive courses serve to align the shingles in vertical rows thus eliminating the making of marks on the roof at regular intervals as are required where non-central locking means are employed. Further, because of the T-shaped character of the locking devices and the fact that they are rigidly clamped to the shingles the laying of the shingles with respect to each other may be done very accurately and, furthermore, since there are no ends of the shingle locks protruding beyond the edges of the shingle the locks are not liable to become damaged in packing or shipment.

From the foregoing it will also be seen that each of the locking devices 7 when turned back upon itself not only serves to lock the abutting corners 12 of adjacent shingles but the turned back portion 9 also serves as a lock for the turned back corner 5 of the shingles of the next course.

While locking member 7 shown in Figs. 1 to 6 as T-shaped it will be understood that any other form of locking strip may be employed. For example, a simple straight strip such as shown in Figs. 9 and 10 may be employed, this strip being fastened to the shingle by any suit-

able means such as the struck-up lugs 20 and 21. In other words, the locking device of Figs. 9 and 10 is substantially the same as the locking device 7 of Figs. 1 to 6 with the horizontal portion 8 omitted. The manner of using the locking device of Figs. 9 and 10 is substantially the same as that hereinabove described, the said locking device being adapted to be bent back upon itself so as to lock the abutting corners of adjacent shingles similar to the manner in which the portion 9 of the above described locking devices is employed.

It will be understood, of course, that while the invention discloses the use of shingles of a square or diamond shape that any other shaped shingle may be employed so long as the shingle is provided with a turned back corner and the turned back edge is perforated to allow the free egress of water and the shingles provided with a locking device for locking the abutting corners of adjacent shingles in the next course.

Various changes and modifications may, therefore, be made in the details of the shingles and the manner of laying them without departing from the spirit and scope of the invention.

What I claim is:

1. A shingle having at least one turned-back edge, said edge being perforated to allow the free passage of water therethrough.
2. A shingle according to claim 1, wherein the body of the shingle is made of flexible material.
3. A shingle in the form of a polygon having one corner folded back, the edge of the fold being perforated to allow water to freely pass therethrough.
4. A shingle of the class described, having one folded back corner and a metal member fastened to the body of said shingle adapted to be bent back upon itself to lock the corner of an over-lying shingle.
5. A shingle of the polygonal type having a turned-back perforated corner, and a shingle lock strip permanently fastened to the body of the shingle, said strip lying on a diagonal line joining opposite corners of the shingle.
6. A shingle according to claim 5, in which

50

55

60

65

70

75

the locking strip is substantially T-shaped and is fastened to the shingle at the ends of the short arm of the T.

7. A shingle according to claim 5, in which the lock strip is adapted to be bent back upon itself. 80

8. A starter shingle having a slit in opposite edges thereof, and a shingle lock member permanently attached to the shingle centrally thereof. 85

9. In combination, a first shingle having a folded back lower edge, a slit in said folded edge, another shingle having a perforated folded back tongue adapted to enter said slit and partially lock the shingles. 90

10. In combination, a shingle having a T-shaped lock strip fastened thereto, a pair of adjacent shingles overlying the first shingle and having abutting corners on the T-shaped lock strip, said lock strip having a portion adapted to be bent back upon itself to grip said corners and lock the shingles together and a cover shingle thereover with a turned back corner engaging the lock strip. 95

11. The combination according to claim 10, in which each of said overlying cover shingles has the turned-back lower corner provided with a perforation to prevent water backing up underneath said shingles. 100

12. In combination, a pair of polygonal shingles laid adjacent to each other with the upwardly converging edge of the shingles meeting to form an angle, a third shingle having a bent-back corner adapted to fit within said angle, and means comprising a flat metal strip adapted to be bent back upon itself for locking 110 the abutting corners of the first mentioned corners and the folded-back corner of the said third shingle. 110

13. The combination according to claim 12, in which the said folded-back corner has the converging edges thereof cut away to allow the shingle to adapt itself to expansions and contractions of the roof or other structure to which the shingles are fastened. 115
